ABRASIVE TREATER

George C. Beck, Spokane, Wash.

Application September 7, 1937, Serial No. 162,603

11 Claims. (Cl. 51—184.4)

This invention relates to improvements in devices for treating the walls of cylinders of explosion engines.

It is well known that after a cylinder grinder has been used with the customary emery and burnishing stones, minute particles of emery remain on the cylinder wall and these particles cause very objectionable wear on the piston rings.

Now it is an important object of this invention to abrasively treat the wall of the cylinder to remove this objectionable condition and provide an entirely smooth and burnished surface for ring travel.

It is also well known that wear on the upper travel portion of a cylinder will enlarge the same to such an extent that it will be tapered with respect to the lower portion of the cylinder, and it is of great advantage, as is well understood, to be able to remove this taper and restore the cylinder to a true cylindrical form.

Now it is a feature of this invention to equip this device with means whereby the same may be used as a grinder to remove the taper in a cylinder, and after this has been done, the device can be equipped to smooth off the ground portion of the cylinder, and also remove emery or metal particles resulting from the grinding treatment.

It is a feature of the invention to provide a plurality of backing strips to which an abrasive strip or strips may be connected, these backing strips being relatively loosely assembled and semi-floatingly or pivotally connected with a driving means so that the assemblage may readily assume either a concentric or tapered relationship relative to the centrally disposed driving means.

It is a further feature to tension the backing strips so that they will normally tend to contract toward the smallest diameter and to provide sufficient strips of the required length so that at all diameters, the strips will form a backing for the abrasive consisting of a multiplicity of thicknesses whereby an ample circumferential resilient backing will always be provided to sustain the abrasive action against the cylinder wall.

The invention has many other features and objects which will be more fully described in connection with the accompanying drawing and which will be more particularly pointed out in and by the appended claims.

In the drawing:

Fig. 1 is an end view of the device looking toward the lower end and showing the backing strips in an expanded and separated position

which they would assume before being inserted into a cylinder.

Fig. 2 is a vertical sectional view on line 2—2 of Fig. 1.

Fig. 3 is a sectional view on line 3—3 of Fig. 2, showing the device in a cylinder but exaggerating the thicknesses of various parts and illustrating the device before the same has been expanded.

Fig. 4 is a fragmental sectional view of portions of the device showing the relationship when the parts are contracted to a small diameter.

Fig. 5 is a view of one of the pivot rods in side elevation.

Fig. 6 is a view of the same in edge elevation.

Fig. 7 is a detail view showing how the abrasive may be secured to one of the backing strips.

Fig. 8 is a plan view of a novel form of abrasive.

Fig. 9 is a sectional view on line 9—9 thereof showing the same on an enlarged scale.

Fig. 10 is an enlarged sectional view of one of the pivot rod sleeves.

Fig. 11 is a sectional view on line 11 of Fig. 2.

Like characters of reference designate similar parts throughout the different figures of the drawing.

In the form shown, 1 designates a driving spindle having a coupling head 2, with studs 3, adapted to be connected with a universal joint or any desired form of coupling with which the selected motive power is equipped. Said spindle 1 is shown to be exteriorly threaded at 4, substantially throughout its length, and at its lower end, said spindle is provided with a plurality of pivot lugs 5, preferably four in number, in the form shown. It will be understood that spindle 1, not only imparts rotary motion to the device but also advances the latter longitudinally of the cylinder, as is customary in devices of this nature. Connected with this driving or propulsive spindle 1 are a plurality of propulsive and expanding or spreading cam bars which, in this construction, are four in number. As all the cam bars are identical in form and function, only one need be described in detail although all are generally designated at 6. Each bar 6 is of U-shaped cross section having a web 7 and flanges 8, the edges 9 of the latter forming cam tracks. The lower ends of bars 6 are connected with lugs 5 by pivots 10 of any desired form, and from this pivotal connection, the bars 6 extend radially outwardly at an upward inclination in the manner clearly shown in Fig. 1.

Reference will next be made to an improved cam means for adjusting the bars 6 to cause

expansion or permit contraction of the backing strips, to be later described.

This cam means, in the present showing, consists of a cam sleeve 11, in threaded engagement with spindle 1 and having on its upper end an adjusting head 12 provided with spanner openings 13 into which spanner rods may be inserted to cause a relative longitudinal adjustment of the spindle member 1 and cam member 11, as a result of turning one member relative to the other, as will now be clear. The lower end of said sleeve 11 is flared at 14 to form a bell-shaped cam adapted for engagement with the cam tracks 9 of the cam bars 6 to expand or permit contraction of the latter, as will now be clear.

Reference will next be made to the novel backing strips and to the manner in which they are assembled.

In the present construction, these backing strips 20 are four in number but this is not an essential or arbitrary number since one or more can be successfully used but the present number affords and offers special advantages which will be fully appreciated in view of the present disclosure. As 25 all of the backing strips are identical in form and function, only one need be described in detail.

These flexible strips are preferably formed of thin clock spring steel of a length less than the complete diameter of the circle of the cylinder. 30 As shown, 15 designates a backing strip the thickness of which is shown in Fig. 1, and the width of which is shown in Fig. 2. This strip is advantageously tensioned to normally contract toward the smallest diameter of cylinder in which the 35 device can be used, and expansion of the strip is effected against its tension.

The free advance end of strip 15 is designated at 16 and the following or trailing end is provided with a hollow sleeve 17, which, as shown in 40 Fig. 10, may consist of a cylindrical sleeve 17, having its flanges 18 secured as at 19, to the end of the backing strip 15. The sleeve thus formed is provided with an opening having an upper margin 18' and a lower margin 19' which are the margins of the opening longitudinally of the 45 sleeve. Circumferentially, the opening is shown in Fig. 11 as having margins 20, the purpose being to afford a pivotal connection as will presently appear.

A pivot or propulsive and expanding rod 21, which is also an equalizing rod, is disposed in said sleeve to fit relatively loosely therein as regards relative rotary movement of said sleeve with respect to said rod. As clearly shown in 50 Figs. 2 and 4, the rod 21 extends practically coextensive with the length of the sleeve 17 and is provided with a pivot lug 22, which extends laterally from the body of said rod 21, as shown in Fig. 5. A cam track 23 extends upwardly from said lug and at an incline, it merges into rod 21 and forms with said lug 22, a projection adapted to extend through the opening formed in sleeve 17, whereby the sleeve 17 will be hinged connected with said rod 21 so that the backing strip can, to a limited extent, which is all that is necessary, relatively rotate with respect to and about 55 rod 21. As will be seen by reference to Figs. 5 and 6, the rod 21 is flat, in the construction shown, and while this is a convenient cross section, it is not an essential one. The desirable feature is that the sleeve 17 should fit relatively loosely about the rod 21, by which it is incidently supported. The supporting engagement is effected by endwise engagement between margin 60 18' and track 23, as regards the upper engage- 70

ment, and margin 19' and lug 22, as regards the lower engagement.

It will be seen from Fig. 3, that the direction of rotation is clockwise and that the rods 21, with the surrounding sleeves 17, form expansion elements which serve to expand the normally contracting backing strips 15 radially outwardly against the cylinder wall A. It will also be noted that all the strips 15 are disposed outwardly with respect to the expanding elements 10 so that when the latter are expanded, they will 15 act upon all the strips. The arrangement is such that the strips 15 overlap each other at all diameters and hence always present a backing consisting of a multiplicity of thicknesses in forcing 15 the abrasive strips, to be later described, against the cylinder wall A.

I now wish to draw attention to the fact that the bars 6 are pivoted at 24 to lugs 22 to complete the propulsive and supporting connection 20 between the spindle 1 and the assemblage of backing strips 15, and that the axes of these pivots 24 are not only disposed substantially midway of the height of the backing strip assemblage but at right angles to the axis about which 25 the assemblage is rotated. Thus it will now be clear how the strip assemblage can not only position itself automatically in the cylinder, but it will also be clear how the assemblage can assume either a concentric relationship with respect to 30 spindle 1, or a tapered relationship thereto.

It will also be clear that the cam tracks 9, of the bars 6, are so disposed by reason of the proportions and the manner in which they are pivoted to the lugs 22 that the tracks 23 will form a 35 contiguous extension of the tracks 9, so that with a small diameter adjustment the cam 14 can ride up onto tracks 23, as will be clear by reference to Fig. 4.

As all the advance free ends 16 of the strips 15 40 will normally abut against the periphery of the next adjacent strip, as will be seen from Figs. 1 and 3, it will be clear that in some instances I may employ this gripping action effectively to connect the abrasive strips thereto without what might otherwise amount to securing the same in the sense of an actual fastening means, as will presently appear. Further, I desire to point out that the resilient strips 15 are strong enough to be self stable but are of amply sufficient 45 strength to stand an appreciable degree of compression stress without becoming deformed from their original shape, and I have successfully used number fifteen thousands gauge clock spring steel in the performance of the function set forth.

Reference will next be made to the abrasive means and to the manner in which it is used.

In light duty service, such as smoothing the cylinder wall, I have successfully used sandpaper where I desire merely to remove emery and metal particles resulting from previous grinding or honing. However, in heavy duty service where I desire to remove the taper of the cylinder and actually take off some stock from the block, I employ a type of emery paper and in some instances, after using the emery paper I may subsequently employ sand paper to remove emery particles.

In either event the width and the length of either type of abrasive will usually be the same, the width being slightly wider than the width of the backing strip assemblage and the length being sufficient to cause the trailing end to slightly overlap the advance end, in case only one length of abrasive is used, as illustrated on Fig. 3.

As shown in Fig. 3 the advance end of the 75

abrasive strip 25, which is indicated at 26, is looped about the advance end 16 of one of the backing strips 15 with the inner portion 27 disposed between the outermost strip 15 and the 5 next innermost strip 15, the contracting tension of the strips serving to hold the folded or looped end without requiring any actual fastening means. However, a fastening means is shown in Fig. 7, which may consist of a U-shaped sheet 10 of metal 28 which may be clamped about the folded advance end of the abrasive strip, and which may be used instead of the expedient shown in Fig. 3. Therefore, hereinafter, whenever I use the term "connected" in reference to 15 the relation of the advance end of the abrasive strip and backing strip, I mean merely any expedient that will serve to hold the advance end of the abrasive strip on the backing strip.

The remainder of the abrasive strip 25, which 20 extends about the periphery of the backing strip assemblage, and wherein the extreme trailing end is shown at 29, is entirely free and unconnected with the assemblage of backing strips and presents its abrasive face against the cylinder wall in an effective manner to smooth or reduce the same. However, in practice, I have successfully used an abrasive strip less in length than the circumference of the cylinder wall to be treated.

30 It is not necessary that a single abrasive strip be used as relatively short abrasive strips may be connected with the ends of several or all of the backing strips if desired, with the trailing end of one strip overlapping the advance end of another strip, although this is not necessary to a 35 successful operation. I have found that when I employ one abrasive strip the remaining backing strips act most effectively when expanded in holding the abrasive strip into sustained and uniform engagement with the cylinder wall.

40 In Figs. 8 and 9 I have shown a form of abrasive strip designated at 30, which is of emery and especially adapted for heavy duty service, the emery or like surface being indicated at 31, and the foundation at 32. It is a feature of this 45 abrasive that it is self-clearing with respect to emery or metal particles and this is accomplished by providing the surface 31 with a series of grooves 33. These grooves extend at a slight angle to the length of the strip so that at all 50 times the abrasive surface 31 will present an effective area to the wall of the cylinder. It will readily be apparent that if the grooves extended longitudinally of the strip, or at right angles to its length, the abrasive surface would be interrupted by the grooves in the first instance, and in the second instance, the grooves would not be 55 self-clearing. It is therefore desirable to groove the strip substantially longitudinally or nearer a lengthwise disposition than any other disposition.

While the operation may be clear from the foregoing, it will be briefly described as follows:

When the device is lowered into the cylinder, 60 the expanding elements are contracted and after insertion, the elements are expanded to dispose the abrasive into engagement with the wall of the cylinder, with a fairly light pressure.

Then rotative thrust is applied to spindle 1 to 65 rotate the device in a clockwise direction whereby the free advance ends of the backing strips 15 will be in a forward relation to the trailing sleeved ends 17, with respect to this direction of rotation. Of course, with a counter-clockwise direction of rotation, the relationship

would be the reverse. Hence, it is essential to this invention that the free ends of the backing strips be in advance of the trailing ends thereof.

Now it will be clear that frictional drag generated on the abrasive strip will cause the backing strip to which it is attached, to bow radially outwardly in such an effective manner that abrasive pressure against the cylinder wall will be substantially uniform throughout the length of the strip, and this is true irrespective of 10 whether the abrasive strip is of sufficient length to overlap as shown in Fig. 3. The importance of this pressure advantage will be realized when emphasis is laid to the fact that the expanding elements are circumferentially spaced and hence 15 if it were not for this bowing of the backing strip, and the multiplicity of thicknesses of backing strips, the pressure engagement would possibly not be as uniform between the expanding elements as abreast of the same. Now if the direction 20 of rotation were in the opposite direction from that indicated in Fig. 3, with the hinged or sleeved end of the backing strips foremost, then, the tendency would be for the backing strip connected with the abrasive strip to pull 25 away from the cylinder wall, especially since the backing strip normally tends to contract toward a smaller diameter.

It will also be seen that when the expanding elements are expanded, irrespective of the diameter to which the device has been adjusted, there will be a multiplicity of thicknesses of 30 backing strips into engagement with the cylinder wall and this increases the efficiency of the device in achieving uniformity of pressure engagement of the abrasive element with the cylinder wall. This is true irrespective of whether one abrasive strip is used, as shown, or whether short abrasive strips are attached to the 35 backing strips.

It will also be clear that when the device is 40 inserted into a cylinder, it will center itself automatically by reason of the pivotal connection through which rotative thrust is imparted, and that the backing strip assemblage is free to 45 assume a cylindrical position in the cylindrical portion of the cylinder, or a tapered position in the lower tapered portion of the cylinder. Further, after the tapered portion has been ground to cylindrical form, by the use of a heavy duty 50 abrasive, or as it is being so changed, the assemblage will gradually change back to a cylindrical form automatically.

It will be seen that the assemblage of backing strips 15, which define a cylindrical abrasive 55 backing, are loosely assembled because of the play afforded the rods 21, in sleeves 17, and that the assemblage is semi-floatingly mounted by reason of the fact that the rods 21 are pivoted between their ends to adjusting bars 6 and are 60 therefore equalizing bars which insure uniform pressure engagement of the abrasive with the cylinder wall irrespective of whether the assemblage assumes a cylindrical or tapered form.

It is believed that the invention will be fully 65 understood from the foregoing description, and while I have herein shown and described one specific form of the invention, I do not wish to be limited thereto except for such limitations as the claims may import.

I claim:

1. In a cylinder smoother and emery removing device, a rotatively driven spindle, a plurality of propulsive expanding cam bars pivoted thereto, a cam adjustable on said spindle for expanding or 75

permitting contraction of said bars, a backing strip supporting and equalizing rod for each cam bar and said rods being pivoted to their respective bars between the ends of said rods whereby said rods may assume a concentric or tapered relation to said spindle, a substantially cylindrical resilient backing strip for each rod and each strip having an advance free end and a trailing propulsive end with respect to the direction of rotation of said device, and the propulsive trailing end of each strip being pivotally sleeved on its respective rod and said backing strips being disposed in circumferential overlapping relation about said spindle and being tensioned to normally contract to the smallest diameter, whereby an abrasive strip may be connected with the free end of one of said backing strips and extend about the remaining backing strips in free trailing relation for uniform engagement with the cylinder wall.

2. In a rotary cylinder smoother and emery removing device, a plurality of expansible resilient backing strips of substantially cylindrical form and in circumferentially overlapping relation to afford a plurality of backing thicknesses at any diameter and said strips being tensioned to normally contract toward the smallest diameter and each strip having an advance free end and a propulsive trailing end with respect to the direction of rotation of the device, a propulsive rod loosely and pivotally sleeved in the trailing end of each strip whereby the overlapping strips will form a relatively loose assemblage capable of assuming a concentric or tapered form about the axis of rotation, whereby an abrasive strip has one end connected with one advance end of one of said backing strips and the remainder of the abrasive strip trailing freely about the strip assemblage for engagement with the wall of the cylinder, and mechanism inside said strip assemblage and pivotally connected with said rods for expanding and propelling said assemblage.

3. In a rotary cylinder smoother and emery removing device, a plurality of expansible resilient backing strips of substantially cylindrical form and in circumferentially overlapping relation to afford a plurality of backing thicknesses at any diameter and said strips being tensioned to normally contract toward the smallest diameter and each strip having an advance free end and a propulsive trailing end with respect to the direction of rotation of said device, an abrasive strip having one end connected with one advance end of one of said backing strips and the remainder of said abrasive strip trailing freely about the strip assemblage for engagement with the wall of the cylinder, and mechanism operatively connected with the propulsive ends of each backing strip for rotating and expanding the strip assemblage.

4. In a rotary cylinder smoother and emery removing device having circumferentially spaced expanding elements, a substantially cylindrical resilient backing strip having an advance free end and a following propulsive end relative to the direction of rotation of said device and the propulsive end being hinged to one of said expanding elements to dispose the radially inner face of said strip abreast of said elements, and an emery abrasive strip having one end thereof connected with the advance free end of said backing strip and the remainder of said abrasive strip trailing abreast of the radially outer face of said backing strip for pressure engagement against the wall of the cylinder when said elements are expanded.

whereby friction drag against the forward end of said abrasive strip will bow said backing strip radially outwardly and cause a uniform pressure engagement of said abrasive strip against the cylinder wall throughout the length of said abrasive strip.

5. In a rotary cylinder smoother and emery removing device having spaced expanding elements, a resilient backing strip having free advance and following ends with respect to the direction of rotation of the device and the following end of said strip being propulsively connected with one of said elements and said strip having a length forming less than a complete circle, and an emery abrasive strip having one end thereof connected to said free advance end of said backing strip and the remainder of said abrasive strip trailing freely abreast of the radially outer face of said backing strip for engagement with the cylinder wall when said elements are expanded, whereby friction drag against said abrasive strip due to propulsion of the rear end of said backing strip will bow the latter outwardly and cause a uniform pressure engagement of said abrasive strip with the cylinder wall throughout the length of said abrasive strip.

6. In a rotary cylinder smoother and emery removing device, an expansible mechanism adapted to be rotated in a cylinder, a backing strip having its rear end, with respect to rotation, propulsively connected with said mechanism and its forward end free, and an abrasive strip having one end connected with the free end of said backing strip and the remainder trailing abreast of said backing strip for engagement with the cylinder wall when said mechanism is expanded, whereby friction drag against said abrasive strip due to propulsion from the rear end thereof will bow said backing strip outwardly and lengthwise tension said abrasive strip and cause uniform engagement of the latter against the cylinder wall.

7. As a new and useful article of manufacture of the class described, a substantially cylindrical resilient backing strip having an advance free end and a following propulsive end with respect to its intended operative direction of rotation, said propulsive end having a propulsive connecting means, and an abrasive strip having one end connected with said advance end of said backing strip and the remainder of said abrasive strip being otherwise free from connection with and trailing abreast of said backing strip toward the propulsive end of the latter.

8. As a new and useful article of manufacture of the class described, a substantially cylindrically shaped resilient backing strip having an advance free end and a following propulsive end with respect to its intended operative direction of rotation, said propulsive end having one member of a hinge connection, a rod forming the remaining member of a hinge connection with the propulsive end of said strip, and an emery abrasive strip having one end connected with said advance end of said backing strip and the remainder of said abrasive strip being otherwise free from connection with and trailing abreast of said backing strip toward the propulsive end of the latter.

9. In a cylinder smoother and emery remover, a device having a plurality of expansible rods, a cylindrically shaped backing strip having an advance free end and a following propulsive end and the latter having a portion for coaction with

one of said rods to form a hinge connection, and an abrasive strip having one end connected with said free advance end of said backing strip and the remainder of said abrasive strip trailing freely 5 abreast of the outer face of said backing strip for engagement with a cylinder wall.

10. In a rotary cylinder smoother and emery removing device, a driving spindle, a cam bar pivoted to said spindle and having a cam track, 10 an expansible backing strip extending about said spindle and having a sleeve provided with an opening, a rod in said sleeve having a pivot lug extending through said opening and pivoted to said bar and said rod having a cam track forming 15 a contiguous extension of the cam track of said bar irrespective of the degree of expansion of said strip, and an adjusting cam on said spindle for coaction with the cam track of said bar and the cam track of said pivot lug.

11. In a rotary cylinder smoother and emery removing device, a relatively loose assemblage of flexible abrasive backing strips of substantially cylindrical form and in circumferential overlapping relation to afford a plurality of backing 5 thicknesses and define a substantially cylindrical abrasive backing at any diameter and each strip having an advance free end and a trailing propulsive end with respect to the direction of rotation of the assemblage, the free end of at least one strip being adapted for connection with one 10 end of an abrasive strip with the remainder of the latter trailing about said assemblage for engagement with the wall of the cylinder, and mechanism in semi-floating connection with said backing strips near the propulsive ends thereof for rotating and expanding said strip assemblage. 15

GEORGE C. BECK.
